(57) **CLAIM**

The ornamental design for a shoulder and tread for a tire, as shown and described.

DESCRIPTION

FIG. 1 is a perspective view of a shoulder and tread for a tire showing our new design, it being understood that the pattern repeats uniformly throughout the circumference of the tread;

FIG. 2 is a front elevational view thereof;

FIG. 3 is a right side elevational view thereof; the opposite side elevational view being identical thereto; and,

FIG. 4 is an enlarged fragmentary front elevational view thereof.

In the drawings, the broken lines defining the center treads, sidewall, inner bead and the peripheral boundary between the tire tread and the sidewall in are for illustrative purposes only and form no part of the claimed design.
